CLAIM

The ornamental design for a shoe as shown and described.

DESCRIPTION

FIG. 1 is a front, top, and right side perspective view of a shoe embodying our new design.

FIG. 2 is a top and right side perspective view thereof.

FIG. 3 is a top and left side perspective view thereof.

FIG. 4 is a front and top perspective view thereof.

FIG. 5 is a back and bottom perspective view thereof.

FIG. 6 is another front and top perspective view thereof; and,
FIG. 7 is a back and top perspective view thereof.

Broken lines are used to illustrate features of the shoe which form no part of the claimed design in the current numbered figures. For example, broken lines showing the collar and any interior portion of the shoe, portions of the knob, the logos, and the mounting features on the bottom of the shoe form no part of the claimed design in the current numbered figures. Dot-dashed broken lines are used to illustrate stitching which forms no part of the claimed design in the current numbered figures.
